DESIGN FOR A VEHICLE LAMP

David M. Morgenstern, Cleveland, Ohio

Application February 9, 1948, Serial No. 144,356

Term of patent 7 years

(Cl. D48—32)

To all whom it may concern:

Be it known that I, David M. Morgenstern, a citizen of the United States, residing at Cleveland, in the county of Cuyahoga and State of Ohio, have invented a new, original, and ornamental Design for a Vehicle Lamp, of which the following is a specification, reference being had to the accompanying drawing, forming part thereof, wherein: Fig. 1 is a front elevational view; Fig. 2 is a rear elevational view; Fig. 3 is a side elevational view, and Fig. 4 is a plan view of a vehicle lamp showing my new design.

I claim:

The ornamental design for a vehicle lamp, as shown.

DAVID M. MORGESTERN.
